UNITED STATES PATENT OFFICE.

HERMANN JENSEN, OF COPENHAGEN, DENMARK.

AUTOMATIC SALES DEVICE.

1,241,984.

Specification of Letters Patent.

Patented Oct. 2, 1917.

Application filed October 12, 1916. Serial No. 125,300.

To all whom it may concern:

Be it known that I, HERMANN JENSEN, of Copenhagen, Denmark, No. 4 Svanemosegaardsvej, have invented new and useful

5 Improvements in Automatic Sales Devices, of which the following is a true and exact description.

My invention concerns an arrangement of automatic sales devices, and the object of 10 the invention is partly to insure the reliable closing of the space for the goods, against the use of worn coins, or those which are too small, and partly to permit the opening of the door in the simplest possible manner, 15 when a proper coin is thrown in.

The invention is shown in the drawing, where—

Figure 1 shows a side view.

Fig. 2 shows a section through the mechanism for separating bad coins from the good coins.

The automatic device consists of one, or several compartments each provided with a door 1, which turns on its lowest rim 2 25 where a weak spiral spring is placed, which deadens the fall forward, when the door is opened. To one side frame of the door is fastened a quadrant plate 3 (the lockwing).

On the rim of this plate is a notch 4, and 30 under this a heel 5 protruding a little. Against the rim of lockwing 3 is pressed a stopper 7, by means of a spring 6, the former revolving around a pin 8. The stopper 7 has a strengthening member 9, through 35 which a small pointed screw 10 is carried. The chute 11 for the coins is slightly inclined, and only permits one coin of the desired kind to pass at a time. The coin chute 11 terminates in a closed part 12, 40 which emerges above the funnel 13. This latter has on the right side a notch 14, through which the point of screw 10 enters the funnel.

When no coin is inserted, the stopper 7 on 45 the handle of the door being pulled will enter the notch 4 and thus lock the door. When a proper coin is inserted it will, as shown in Fig. 1, prevent a forward movement of screw 10, by jamming itself firmly 50 between screw 10 and the opposite wall of funnel 13. The stopper 7 can thus not move farther forward and by a turning of the door notch 4 will pass by the point of stopper 7 without the stopper 7 interfering with 55 the movement of the door.

When the heel 5 of the lockwing 3 passes

the point of stopper 7 it will force this latter a little back, which will remove screw 10 from the coin, which latter will fall down through chute 15 to drawer 16. In order to 60 separate worn coins, a piece of the bottom of the coin chute 11 is cut away, and the missing part is replaced by a loose piece 17 fastened by some elastic wire 18 which turns on a pin 19 fastened to chute 11. From the 65 pin 19 extends an arm 20 in the end of which is a screw 21, of which the point, when the door is closed, enters into a small groove 22 in lockwing 3.

When a normal coin is inserted, this latter 70 runs smoothly along the piece 17, the upper edge of which is rather sharp. If the coin is too thin, it will jam between piece 17 and the back of the coin chute, and on the handle of the door being pulled the point of 75 screw 21 is moved out of the groove 22 of the lockwing 3 and the coin is released, and falls down through a suitable chute into a bowl 23. Door 1 can, when no coin is found opposite screw 10, not turn more than the 80 small part represented by the distance from the point of stopper 7 to the notch 4. This small turn is however sufficient to bring the point of screw 21 out of the groove 22 in the lockwing 3, so that arm 20 turns sufficiently 85 for piece 17 to release the jammed worn coin.

Coins of a too small diameter will pass screw 10 without being held. It will easily be seen that this arrangement by very few 90 mechanical means acts reliably, and does not react with worn or too small coins.

Having now described my invention, what I claim as new and desire to secure by Letters Patent is:

1. In a sales device, a coin chute, a door having on its inner face an inwardly projecting member, and a movable locking member projecting into the coin chute to retain a coin therein, and coöperating with 100 the member of the door to lock the same when there is no coin in the said chute and held in inoperative locking position by a coin in the chute to permit the door to be opened.

2. In a sales device, a coin chute, a door having an inwardly projecting member on its inner face and a pivoted and spring pressed locking member projecting into the chute to retain a coin therein, and coöperating 110 with the member of the door to lock the same when there is no coin in the chute

and held in inoperative locking position by a coin in said chute to permit the door to be opened, and means for operating the locking member when the door is opened to release the coin.

3. In a sales device, a coin chute, a door having a quadrant shaped and notched member on its inner face and a pivoted and spring pressed locking member carrying a screw projecting into the coin chute to retain a coin therein and adapted to engage the notch of the door member to lock the door when there is no coin in the chute, said locking member being held out of engagement with the said notch by a coin in the chute, and means on the door member for operating the locking member to release the coin when the door is opened.

4. In a sales device, a door having an inwardly projecting member on its inner face, a coin chute having an opening in its bot-

tom, a resiliently mounted member in the opening of the chute, and means coacting with the member of the door for permitting the member in the opening of the coin chute to release the coin when the door is opened.

5. In a sales device, a door having an inwardly projecting member on its inner face, said member being provided with a recess, a coin chute having an opening in its bottom, a wedge shaped member resiliently supported on the chute and located in the opening of the said chute and an arm connected with the resilient supporting means of the said wedge-shaped member and provided with a screw normally engaging the recess of the door member.

Signed by me at Copenhagen, Denmark this 12th day of September, 1916.

In testimony whereof I affix my signature.

HERMANN JENSEN.
